(57) **CLAIM**

The ornamental design for an information processor and router, as shown and described.

DESCRIPTION

FIG. 1 is a front perspective view of an information processor and router showing our new design;

FIG. 2 is a front elevation thereof;

FIG. 3 is a top plan view thereof; and,

FIG. 4 is a right side elevation thereof, the side opposite being a mirror image.

The broken line showing of environment in the figure drawings is for illustrative purposes only and forms no part of the claimed design.
